ATTORNEY

UNITED STATES PATENT OFFICE.

CHARLES EDWARD HAVILAND, OF LIMOGES, FRANCE.

DESIGN FOR A COVERED DISH OR SIMILAR ARTICLE.

SPECIFICATION forming part of Design No. 32,872, dated June 26, 1900.

Application filed May 31, 1900. Serial No. 18,681. Term of patent 7 years.

To all whom it may concern:

Be it known that I, CHARLES EDWARD HAVILAND, a citizen of the United States, residing at Limoges, in the Republic of France, have 5 invented and produced a new and original Design for a Covered Dish or Similar Article, of which the following is a specification, reference being had to the accompanying drawings forming a part thereof, and in which—

10 Figure 1 is a side elevation of a dish bearing and incorporating my design; and Fig. 2 is a top view, partly broken away, of same.

The leading features of my design consist 15 of the ornamental form and configuration of the dish and its cover, substantially as illustrated in the drawings.

In the drawings, A indicates the body of the dish, and B the cover therefor. The body A has the downwardly and inwardly curved 20 side surfaces and comprises the correspond-

ing scalloped sections C, which terminate at the ornate scalloped base D, the latter bearing along its edges the scroll configuration E. Along the upper edges of the body A is the ornate scalloped scroll configuration F. 25 The cover B has a raised central portion bearing at its apex the handle G, and along its scalloped edges said cover bears the ornate scalloped scroll configuration H, corresponding with the ornamentation F on the upper 30 edges of the body A.

What I claim is—

The design for a covered dish or similar article; substantially as shown and described.

Signed at Paris, in the Republic of France, 35 this 17th day of May, A. D. 1900.

CHARLES EDWARD HAVILAND.
